ELECTRIC SWITCH

Josef J. Zeller, Wauwatosa, Wis., assignor to
 Square D Company, Milwaukee, Wis., a corpora-
 tion of Wisconsin

Application June 29, 1949, Serial No. 101,985

7 Claims. (Cl. 200—83)

1

This invention relates to electric switches and refers particularly to pressure switches of the type used with air compressors and water pumps, but capable with slight modification of being float actuated to maintain a predetermined level of liquid in a tank.

One of the objects of this invention is to provide a switch of the character described which will function equally well when used either as a float switch or as a pressure switch despite the fact that in the one case the actuating force is relatively slight while in the other it may be very substantial.

In this connection it is more specifically an object of this invention to provide an electric switch which will snap open and shut with a positive action regardless of the service for which it is used.

A further object of this invention to provide an improved manner of incorporating a pressure differential spring in a switch of this type, and whereby adjustment of the differential spring in nowise affects the operation of the switch except to the extent that it either increases or decreases the differential between the opening and closing pressures.

Another object of this invention is to provide an improved manner of imparting opening and closing motion to the carrier of the movable switch contacts from the slow movement of the actuating mechanism.

In this connection it is another object of this invention to provide a switch of the character described in which the desired snap action is achieved through use of a bowed leaf spring reacting between two pivoted levers one of which is pivotally connected to the actuating member so that slow movement of the actuating member rocks the same to carry the end of the bowed spring attached thereto across dead center to thereby snap the contact carrier from one position to the other.

Another object of this invention is to provide a switch of the character described which when float actuated includes means to assure against diminishing or indecisive contact pressure as the float gradually rises and the switch tripping point is approached.

A still further object of this invention is to provide a switch of the character described which has a far more lively action than switches heretofore available for this service, and which by its design and construction is exceptionally flexible and may be readily applied to different types of service.

With the above and other objects in view, which will appear as the description proceeds, this invention resides in the novel construction, com-

2

bination and arrangement of parts substantially as hereinafter described and more particularly defined by the appended claims, it being understood that such changes in the precise embodiment of the hereindisclosed invention may be made as come within the scope of the claims.

The accompanying drawings illustrate one complete example of the physical embodiment of the invention constructed according to the best mode so far devised for the practical application of the principles thereof, and in which:

Figure 1 is a side view of a switch embodying this invention, said view showing the switch housing and diaphragm in section and illustrating the switch in its normally closed condition;

Figure 2 is a view similar to Figure 1 but showing only the essential parts of the switch mechanism, with the switch held open by pressure on the underside of the diaphragm;

Figure 3 is a horizontal sectional view through Figure 1 on the plane of line 3—3;

Figure 4 is a front view of the switch showing part of the main spring broken away and illustrating particularly the manner in which the differential spring is incorporated in the assembly.

Figure 5 is a horizontal sectional view through Figure 4 on the plane of the line 5—5;

Figure 6 is a view partially in side elevation and partially in longitudinal section illustrating the switch adapted for float actuation; and

Figure 7 is a sectional view taken through Figure 6 on the plane of the line 7—7.

Referring now particularly to the accompanying drawings in which like numerals indicate like parts throughout the several views, the numeral 5 designates a generally U-shaped main frame for the switch mounted in a housing 6.

If the switch is to be fluid pressure actuated as, for instance, in air compressor or water pump service, a diaphragm 7 is secured across a hole in the bottom wall 8 of the housing by being clamped between the housing bottom wall and a diaphragm head 9. The interior of this head provides a diaphragm chamber connectable with the pressure source. If the switch is to be float actuated the diaphragm head is replaced by a pair of laterally spaced brackets 10 between which a lever 11 is pivoted as at 12, as shown in Figures 6 and 7.

In either case motion is adapted to be imparted to a main lever 13 to actuate the switch mechanism and to open and close the switch which is indicated generally by the numeral 14.

As is customary the switch 14 has pairs of co-operating stationary and movable contacts 15 and

16 respectively, the former mounted upon an insulated terminal block 17 and the latter upon an insulated carrier 18 with individual contact springs 19 for each pair thereof. The terminal block is suitably secured to the main frame 5 by screws 20 which pass through a boss 21 on the underside of the terminal head and are threaded into ears 22 extending in from the upper front portion of the main frame side walls 23. This manner of mounting the terminal head facilitates the adaptation of the switch to either normally open or normally closed service.

The main frame 5 is a stamping and in addition to its side walls 23 which have their front edge portions cut out as at 24, it includes a bottom wall 25, the front and back portions of which are offset downwardly to provide feet upon which the switch mechanism rests. These flat supporting feet are seated upon the bottom wall of the housing 6 above the front and back marginal portions of the diaphragm 7 and are secured in place by screws 26 which pass through the marginal edge portion of the diaphragm head 9, the diaphragm and the bottom wall 8 of the housing to be threaded into the feet.

At its foremost portion the frame 5 has an inclined upwardly directed lip 27 to which a U-shaped bracket 28 is secured. The sides of this U-shaped bracket have aligned notches 29 facing rearwardly. The forepart of the frame also has a lateral projection 30 at one side thereof to which an upright stem 31 is secured in parallel spaced relation to a longer upright stem 32 also anchored to the forepart of the frame medially between the two arms of the U-shaped bracket 28. The longer stem 32 has a main spring 33 mounted thereon while the shorter stem 31 mounts a differential spring 34. This differential spring is normally confined between a shoulder 35 on the stem 31 and an adjusting nut 36 threaded to the upper end of the stem.

The main spring 33 is confined between an adjusting nut 37 threaded on the upper portion of the stem 32 and a shelf 38 resting upon the free end of the main actuating lever 13 to thus at all times yieldingly urge the lever downwardly.

For float actuation neither of the springs just mentioned is required. Hence, these elements are omitted when the switch is to be float actuated.

The main actuating lever 13 is received between the side walls 23 of the main frame 5 and is pivotally connected thereto by a cross pin 39 at a point near the lower rear portion of the frame. The main actuating lever 13 is a U-shaped stamping with its flanges 40 lying closely adjacent to the inner surfaces of the frame side walls. Its web 41 has V-shaped indentations 42 against which pointed fingers 43 extending up from a diaphragm plate 43' bear to lift the main lever against the opposition of the spring 33 in response to pressure in the diaphragm chamber, the fingers 43 passing through holes 44 in the main frame.

Each side wall 23 of the main frame has a hardened plate 45 accurately located thereon and riveted thereto. The front marginal edge of each plate 45 has a V-shaped notch 46 therein in line with the cutout 24 of the side walls of the frame proper. These notches 46 are transversely aligned and receive knife edges 47 projecting rearwardly from the contact carrier 18.

For all intents and purposes, the plates 45 constitute part of the main frame 5 and are separate pieces only to obviate the need for hardening the entire frame to secure the desired hardness for the notches 46. Being flat pieces the plates 45

may be hardened without danger of deformation, as is also the case of the separate U-shaped clip 28.

The contact carrier 18 is preferably made up of two sheet metal stampings 48 and 49 riveted together as at 50. The stamping 48 is essentially a flat lever and has the knife edges 47 formed directly thereof while the stamping 49 is generally a U-shaped structure and has an insulated contact carrying arm 51 secured thereto.

By virtue of the engagement of the knife edges 47 in the notches 46 the contact carrier is rockably supported for movement between switch open and switch closed positions, these limits of motion being defined by the collision of a laterally projecting arm 52 on the lever 48 with either of two stop abutments 53 and 54 both of which are formed as part of the adjacent side wall of the main frame 5.

20 The arm 52 also provides means for opening a pressure relief valve 55 (shown in light lines in Figure 4) as the switch is opened. Such relief valves are customarily employed where the switches are used for the control of air compressors and have as their purpose to bleed pressure from the pressure chamber of the compressor as the compressor stops so that subsequent starting of the compressor will be easier.

Up and down movement of the main actuating 30 lever 13 is imparted to the contact carrier 18 in a novel manner (now about to be described) which assures a more lively switch action and generally improves the operation of the switch. It will be noted that the notches 46 and the notches 29 are 35 opposed to each other, that is, they face each other. The lever 48, which forms part of the contact carrier, is pivoted in the notches 46 and extends forwardly toward the other set of notches 29. Hence, it projects toward an intermediate 40 lever 56 which is embraced by the arms or flanges of the main actuating lever 13 and is pivotally connected thereto as at 57, the pivot being a pin mounted in appropriate holes in the side flanges or arms of the lever 13 and passing 45 through slightly elongated holes 58 in downstruck ears 59 on the intermediate lever 56, the major axis of the elongated holes 58 being parallel with the lever 56.

The lever 56 has knife edges 60 received in the 50 notches 29 and the rear end of the lever opposite its knife edges has a spring seat 61 formed thereon. This spring seat is parallel to and spaced a short distance from a similar spring seat 62 on the lever 48. A bowed leaf spring 63 has its ends 55 hooked onto these spring seats 61 and 62 and yieldingly urges the same apart. Hence, the bowed spring 63 holds the knife edges 47 of the contact carrier in their notches 46 and thereby retains the contact carrier in position and also 60 holds the knife edges 60 of the intermediate lever 56 in their notches 29. Also, depending upon whether or not the pivot 57 is above or below the dead center plane joining the bottom of the notches 29 with the axis of the pivot 39, the bowed leaf spring 63 holds the contact carrier in its switch open or switch closed position respectively.

Thus as shown in Figure 1 as long as the main 70 lever 13 is held down by the spring 33 and the pivot axis 57 is below the defined dead center plane the spring seat 61 will be below the dead center plane joining the bottoms of the notches 29 and 46 and this disposition of the spring seat 75 61 so directs the thrust of the bowed spring that

the contact carrier is yieldingly urged thereby to its switch closed position shown in Figure 1.

As the pressure within the diaphragm chamber overbalances the force of the spring 33 and the actuating lever 13 moves upward the pivot 51 crosses dead center and thereby swings the intermediate lever 56 on its knife edges 60 to the position shown in Figure 2 at which the spring seat 61 is above the dead center plane joining the bottoms of the grooves 29 and 46. With such reversal of the position of the spring seat 61 the thrust of the bowed spring 63 snaps the contact carrier to its switch open position shown in Figure 2. The described relative motion between the main lever 13 and the intermediate lever 56 is permitted by the elongated shape of the openings 58.

The differential spring 34 by which the differential between the pressures at which the switch is opened and closed may be adjusted, is so incorporated in the mechanism as to assure against the possibility of its presence and adjustment affecting the action of the switch in anywise. Hence, the shelf 38 upon which the main spring bears has an arm 65 projecting from one end thereof and apertured to loosely receive the stem 31. When the main lever 13 is in its lowest position in which it is normally yieldingly held by the spring 33, the top of the arm 65, which preferably has two radial ridges 66 at diametrically opposite sides of the stem 31, is spaced from the washer 67 interposed between the bottom of the differential spring 34 and the shoulder 35. Consequently, the main lever 13 may be lifted for a distance without opposition from the differential spring, and since the differential spring always bottoms on the shoulder 35 before the main lever descends far enough to trip the switch closed, closure of the switch takes place at a pressure determined solely by the setting of the main spring.

On the other hand, during elevation of the main lever 13 to trip the switch open, the differential spring 34 is lifted off the shoulder 35 and the load thereof added to that of the spring 33 before the lever 13 has risen high enough to trip the switch. The differential spring thus acts only during opening of the switch and thereby determines the differential between the pressures at which the switch opens and closes; the greater the tension on the spring 34, the higher the pressure needed to open the switch. Therefore, by increasing the tension on the spring 34, which is done by tightening the adjusting nut 36, the span or differential between the opening and closing pressures is increased and vice versa.

Attention is directed to the manner in which the shelf 38 is constructed and mounted upon the free end of the lever 13. It is conveniently made as a channel shaped stamping having upwardly pressed knobs 68 positioned to properly center the main spring and slots 69 in its web to receive upstanding tongues 70 on the flanges of the actuating lever. Forwardly and rearwardly of the tongues 70 the flanges of the actuating lever have bearing shoulders 71 upon which the shelf 38 rests.

The strength of the bowed spring 63 depends upon the service for which the switch is to be used. For air compressors where the opening of the switch is accompanied by the actuation of a pressure relief valve the bowed spring must have maximum strength. For water systems where the opening of the switch does not entail concomitant actuation of a pressure relief valve and

where the pressures involved are generally less than that encountered in air compressor service, a medium strength spring is used. For float actuation a still lighter spring is employed.

When the switch is adapted for float actuation the diaphragm chamber, the main spring 33 and the pressure differential spring 34 are omitted. Consequently, the only force holding the pivoted main actuating lever 13 down is that derived from the relatively light bowed spring 63'. The spring 63' thus, of course, also provides the contact pressure to hold the contact carrier 18 in its switch closing position.

As noted hereinbefore, in this embodiment of the invention a float lever 11 is pivotally mounted on the underside of the switch and this lever, which may be considered the actuator proper, has a motion transmitting connection with the pivoted lever 13 so that as the lever 11 moves up and down with the float it will impart similar movements to the lever 13. The pivot 12 for the lever 11 may be either rearwardly or forwardly of its connection with the lever 13, the former condition being illustrated in Figure 6. In this case ascent of the float lifts the lever 13 to effect opening of the switch and descent of the float lowers the lever 13 to effect closure of the switch.

If the pivot pin 12 is moved from its position shown in Figure 6 and instead passed through a second set of holes 75 and 76 respectively in the brackets 10 and the head of the lever 11, the reverse condition obtains, i. e., ascent of the float closes the switch and vice versa.

The motion transmitting connection between the levers 11 and 13 comprises two parallel transversely spaced links 77 pivoted as at 78 to the lever 13 and to the lever 11 by means of a cross pin 79. The cross pin 79 passes through holes in the lower ends of the links 77 and the flanges 11' of the U-shaped head of the float lever 11.

The clearance between the pin 79 and the holes in which it seats is purposely large to provide a degree of lost motion in the connection between the levers. As long as the lever 11 is in its lowermost position this lost motion is taken up by the weight of the lever. As the float lever 11 rises the lost motion or play, of course, must be taken up in the other direction before motion is transmitted to the lever 13.

The limited freedom for independent motion between the levers 11 and 13 resulting from this play in the connection therebetween enables a coil spring 80 confined between the bottom of the lever 13 and the pin 79 to assure the desired decisiveness in switch action despite the relative weakness of the spring 63'. A bridging piece 81 resting upon the flanges 11' of the float lever and provided with a hole 82 holds the lower end of the coil spring in position bearing upon the cross pin 79, while the upper end of the spring is received in the depressed pocket in the bottom of the lever 13.

The manner in which the spring 80 precludes indecisive contact pressure is as follows: Without the spring 80 and the play or lost motion which it can take up, as the lever 13 rises a point is reached where the contact pressure provided by the light leaf spring 63' balances the contact springs 19 and the contacts begin to "ease off." However, with the coil spring 80 before this point of balance is reached the force stored in the spring 80 overcomes the spring 63' and by virtue of the play or lost motion in the connec-

tion between the levers 11 and 13 snaps the switch open.

From the foregoing description taken in connection with the accompanying drawings it will be readily apparent to those skilled in the art that this invention provides a switch which is very well adapted for either pressure or float actuation and that it possesses many advantages over switches heretofore available for this purpose.

What I claim as my invention is:

1. In an electric snap switch adapted for pressure and float actuation: a frame providing opposed knife edge seats; a contact carrier having knife edges engaging one of said seats, said contact carrier carrying the movable contacts of the switch for movement to and from switch closing position by rocking motion about its knife edges; an intermediate lever having knife edges engaging the other of said knife edge seats, said contact carrier and intermediate lever extending from their respective knife edges towards each other and having adjacent but spaced apart spring seats; a spring tensioned between said spring seats and yieldingly urging said spring seats apart and to opposite sides of a dead center plane connecting the opposed knife edge seats; and an actuating lever pivotally mounted upon the frame and having pivotal connection with the intermediate lever so that rocking of the actuating lever about its pivotal connection with the frame swings the intermediate lever about its knife edges to open and close the switch.

2. In an electric switch of the character described: a frame including spaced side walls provided with notches in the front edges thereof; a carrier for the movable contacts of the switch having knife edges received in said notches; an actuating lever between the side walls of the frame and pivoted thereto, the free end of the actuating lever extending beyond the notched front edges of the side walls and beyond the contactor carrier pivoted therein; an intermediate lever medially pivotally connected to the free end portion of the actuating lever; knife edges on the end of the intermediate lever nearest the free end of the actuating lever; means on the adjacent portion of the frame providing notches in which said last named knife edges are received; a spring seat on the inner end of the intermediate lever; a spring seat on the contactor carrier facing the spring seat on the intermediate lever; and a spring tensioned between said seats and urging them apart to thus snap the contactor carrier from one position to the other as the actuating lever swings on its pivot to carry its connection with the intermediate lever across dead center, the pivotal connection between the intermediate lever and the actuating lever having sufficient lost motion to enable said connection to swing across dead center as the actuating lever swings on its pivot.

3. In a snap switch of the character described: a frame having two pairs of knife edge receiving notches spaced apart and facing each other; a carrier for the movable contacts of the switch having knife edges pivotally received in one of said pairs of notches and adapted to carry the movable contacts of the switch from one position to the other as said carrier rocks upon its knife edges; means for defining the limits of said rocking movement; a main lever pivotally connected to the frame adjacent to said pair of notches in which the knife edges of the contact carrier are pivoted, the free end of said lever being adjacent

to the other pair of notches; an intermediate lever having knife edges pivotally engaged in said other pair of notches and extending therefrom toward the first pair of notches; means pivotally connecting said intermediate lever medially of its ends to the free end portion of the main lever; spring seats on the intermediate lever and the contact carrier spaced apart but facing each other; and a bowed spring confined between said

10 spring seats to yieldingly urge the same apart and thus hold the contact carrier at one or the other of its limits of movement depending upon the position of the main and intermediate levers.

4. The switch of claim 3 further characterized by the provision of a compression spring acting upon the main lever and providing a force tending to rock the lever about its pivotal connection with the frame in one direction; and fluid pressure responsive means acting upon the main lever and providing a force tending to rock the lever in the opposite direction.

5. In a switch of the character described: a frame having spaced side walls, said side walls having knife edge receiving notches opening to the front of the frame; means on the forepart of the frame providing another set of knife edge receiving notches facing rearwardly toward the first designated set of notches; a carrier for the movable contacts of the switch having knife edges received in the first designated notches to mount the contact carrier for rocking motion; a main lever between the side walls of the frame and pivoted thereto on an axis spaced rearwardly and downwardly from the first designated knife edge receiving notches with the free end of the lever adjacent to said other set of notches at the forepart of the frame, said lever having transversely spaced arms; an intermediate lever embraced 40 by the arms of the main lever and medially pivotally connected thereto near the free end of the main lever; knife edges on the intermediate lever engaging in the set of notches at the forepart of the frame; a spring seat on the intermediate lever rearwardly of its pivotal connection with the main lever; a spring seat on the contact carrier facing the spring seat on the intermediate lever; and a bowed leaf spring having its free ends bearing against the spring seats to 45 yieldingly urge the same apart and thereby hold the knife edges of the contact carrier in their respective notches and yieldingly hold the contact carrier in one or the other of its limits of rocking motion depending upon the position of the main and intermediate levers.

6. In a switch of the character described: a movable contact having a contact spring which is tensioned as the switch is closed; a pivoted actuating lever; mechanism connected between the movable contact and the actuating lever for snapping the movable contact from one position to the other as the actuating lever rocks on its pivot, said mechanism including a bowed spring which holds the movable contact in its closed position and thereby tensions the contact spring; an actuator; a motion transmitting connection between the actuator and said pivoted actuating lever, said motion transmitting connection having a degree of lost motion; and a spring reacting between the actuator and the pivoted actuating lever and yieldingly urging said members apart so that during movement of the actuator toward the pivoted actuating lever the lost motion in the connection is taken up before movement is imparted to the pivoted actuating lever, and force

is stored in said spring to snap the switch open before the instant is reached at which the forces of the contact spring and the bowed spring would balance.

7. In a switch of the character described: a frame; a main lever pivoted at one end portion to the frame, said main lever having spaced apart opposing flanges thereon extending to its other end portion and disposed to swing edgewise with the main lever; an intermediate lever received between the flanges on said other end portion of the main lever; a pivotal connection between one end of said intermediate lever and the frame adjacent to said other end portion of the main lever; a motion transmitting connection between the main and intermediate levers whereby pivotal motion of the main lever is translated into rocking motion of the intermediate lever about its pivotal connection with the frame; switch means connected with the opposite end of said intermediate lever to be actuated thereby between switch-open and switch-closed positions; a bridge-like saddle overlying the intermediate lever and said other end portion of the main lever, said saddle seating upon edge portions of the main lever flanges; an interlocking connection between each of said flanges and the saddle hold-

5
10
15

ing the latter against movement relative to the main lever except in a direction to lift the saddle off of said edges of the main lever flanges; and a spring acting upon said saddle to hold the same against movement relative to the main lever in said direction to thus maintain the saddle operatively connected with the main lever, said spring acting through the saddle to apply a force on the main lever yieldingly urging the same and the intermediate lever connected therewith toward a position at which said switch means actuated by the intermediate lever is at one of said switch positions.
